SERVICE SIGNALING SYSTEM

William H. Clehm, Coldwater, N. Y.

Application April 18, 1938, Serial No. 202,646

6 Claims.

(Cl. 177—311)

My present invention relates to signaling and it has for its particular object the provision of a board display register of ordered acts in a place of business whereby units to be entered for attention are registered categorically, the services or operations to be performed upon said units are registered, designations are made in connection therewith of the attention that is being given to specific orders and a time limit for completion is set. The improvements are directed in part to the construction of the display board and to the construction of a manual whereby the control board is manipulated. To these and other ends, the invention resides in certain improvements and combinations of parts, all as will be hereinafter more fully set forth, the novel features being pointed out in the claims at the end of this specification.

In the drawings:

Fig. 1 is a front elevation of a signal board and a manual for control thereof applicable to one class of use;

Fig. 2 is a similar view of a companion board and manual useful in a modified field of operation;

Fig. 3 is an enlarged view partially broken away of the signal board shown in Fig. 1;

Fig. 4 is a top plan or edge view of such board;

Fig. 5 is an enlarged view partially broken away of the manual for the board of Figs. 1 and 3;

Fig. 6 is a diagrammatic view of typical circuit arrangements involved;

Fig. 7 is an end view of the manuals of Figs. 1 and 2;

Fig. 8 is a detail perspective view of one of the workman's jacks used on the manuals for closing certain circuits;

Fig. 9 is a similar view of another jack of the same general nature used for the same purpose under different circumstances;

Fig. 10 is a bottom plan view of the board of the manual of Fig. 1;

Fig. 11 is an end view of the mechanism of Fig. 10 in operative position;

Fig. 12 is a similar view of the same mechanism in inoperative position;

Fig. 13 is a front view of the controlling mechanism of the manual as shown in Fig. 12;

Fig. 14 is an end view of the control mechanism of the manual as shown in Fig. 13;

Fig. 15 is an elevation of the time indicating mechanism, enlarged;

Fig. 16 is a top plan view of the same mechanism on the same scale, and

Fig. 17 is an enlarged elevation of the dial arrangement of the time mechanism units.

Similar reference numerals throughout the several views indicate the same parts.

The invention as herein disclosed has been designed for the purpose of aiding in entering automobiles in a garage or service station and keeping track of operations with respect thereto. For instance, the modern automobile salesroom is also, of necessity, a service station. When a used (second hand) car is sold and before delivery to the customer, it is given a road test; special work may be required to be done thereon as a result of the road test; it is thereafter washed; it is greased; it may have mechanical troubles to be corrected before delivery or metal and paint jobs done with respect thereto.

Somewhat the same as well as different treatment is accorded new cars or customer's cars that are brought in. They are presented for washing, greasing, mechanical trouble, lubrication, etc. There may be an order to attend a wreck and bring in the car and generally with respect to both new cars and old, there is a desire to know where the car came from, where it is in the shop, whether it is to be called for or delivered and the time of day that it shall be ready for delivery. The superintendent or foreman, on the other hand, is also interested in knowing the disposition of his workmen, that is, what man is working on what job, and which men if any are idle. Through the use of this invention he can ascertain all of these facts from consulting jointly the signal board and the manual or keyboard, while the workman in the same way can tell by inspection how many jobs are ahead of him and which requires his more immediate attention.

In the practice of my invention in general, I establish in the shop under the authority of a foreman or general superintendent a board on which by signal the reception of the car is indicated for him and by him. There is next indicated on the board the department to which the car first goes and all of the departments that will be required to service it completely. Arrangements are made whereby a workman in that department accepts the car and registers upon the board the fact that he has it in charge. An original signal calls the workman and a signal operated by him indicates that the ordered act on his part is in process. The workman thus learns from an inspection of the board the cars that are waiting for his attention and the superintendent learns from the board when a specific

car has been taken over for such attention. The superintendent through the use of a time indicator informs the workman the time for which the car has been promised by him for call or delivery and at the same time registers for himself the promise in this respect that he has made to the customer.

Referring more particularly to the drawings, I have illustrated tandem signal boards S and S' adapted to be mounted at an elevated point in a suitable location in the establishment together with manuals individual to each indicated at M and M'. The reason for the two signal boards is that used car service is, as aforesaid, in certain respects, peculiar to used cars, whereas the general servicing of customer's cars and the delivery of new cars are different in their demands in many respects. Therefore, these groups are segregated in order not to overload one board from the standpoint of easy and rapid reading thereof with the signals of the other group not so often used. As the mode of operation and construction of the board S contains substantially everything present in the board S', I have shown and will describe in detail only the board S.

We will assume that the boards are in charge of a superintendent in or near the shops with a corps of workmen under his direction and which superintendent receives from the office in the way of shop tickets the orders that come in. When such an order is received by the superintendent, he writes the necessary data with which he is concerned, such as the name of the purchaser or customer, the motor and the automobile engine number, the State license number, etc., upon an individual card or slip which is inserted in one of a vertical column of slip holders 1 on the manual M, the particular construction and mode of operation of which holders will be later described. The manual is conveniently arranged for writing purposes and other manipulations in the manner of a desk body 2 supported on legs 3 and conveniently carrying the battery 4 for energizing the operating circuits. On the present manual there are 15 of these holders indicating that 15 cars can be received and entertained at one time. Transverse rows of devices on a manual including the respective holders 1 are designated by a vertical column of numbers 5 at the left of the manual and so far as the shop is concerned, a particular car so entered thereafter becomes, for practical purposes, car 1, 7, 15 or whatever it may be and the devices in the corresponding transverse rows apply individually thereto.

Such devices consist of jack plug circuit closing sockets 6, 7 and 8 and finger switches 9, 10 and 11. These plugs and switches are arranged, as shown, in vertical as well as intersecting transverse columns and rows, some of which latter include a plug and a switch and some either one or the other, only, for reasons that will later appear. The heads of the columns on the manual bear designations of specific instructions and specific operations that can be identified by the letterings on the drawings without use of further reference numerals. Reviewing these and reading from left to right in Fig. 6, car No. 1 is either to be delivered to the customer when finished or, if a small job, the customer may wait for it; the car may be a new car just sold and to be prepared to turn over to the purchaser or it may be a wreck that is brought in; all concerned wish to know the time that the repaired or conditioned car is promised; the job ordered may relate to

washing, lubricating, mechanical repair or painting. The last jack column 8 at the right does not relate to the car but to the workman or operator and should be ignored for present purposes, as will be explained.

Turning now to the wall signal board M of Fig. 3, this embodies identical or equivalent designations and representations. It has the left hand vertical column of car numbers 5S running 1 to 10. It has vertical column divisions corresponding to the vertical column divisions of the manual headed and footed with the same designations "Delivery," "Wait," "New car," "Wreck," etc. running across. The areas of these divisions running transversely across the columns are, however, devoted to signals responsive to the switch and signal closing devices of the manual. Taking the case of car No. 1, for instance. These signals comprise a "Delivery" signal 6a, a "Wait" signal 9a, a "New car" signal 9b, a "Wreck" signal 9c, "Wash," "Lubricate" and other signals 11a. There is another vertical column of signal lights under the designation "Operator" which will be later described as stated in connection with the description of the manual.

Such signals, in general, consist of optical lenses or light transmitting glasses of contrasting colors as shown by the hatchings on the drawings. There is also a vertical column under the heading "Time" consisting of luminous clock dials 10a, each provided with a rotary hand 12 which corresponds to and is controlled by the vertical "Time" column of the switches 10 on the manual of Fig. 5.

It is believed that an explanation of the mode of operating the apparatus, as explained up to this point, without further reference to specific structure will hasten an understanding of the mode of utilizing the device. We will suppose that the superintendent receives an order for work on a car driven in and which he enters as car No. 1 in car designating column 5S. His shop card tells him the identification to be placed on the slip in holder 1 which he enters. This reveals the fact (1) that the car is to be delivered when the job is completed, (2) that it is a wreck job, (3) that it is promised the customer at 4 o'clock, (4) that there are mechanical repairs, (5) that metal and paint is to be restored.

Switch 9 on the manual M is a two-way switch and the superintendent throws it in a way that will light signal 6a on the board, each of these signal lenses being provided in the rear with a light bulb 13, controlled by said switches, as shown in Fig. 4. He next throws switch 9 under the column "New car-wreck" on the manual, which is also a two-way switch, in the proper direction to show that it is a wreck case which illuminates the corresponding signal 9c on the board. At this point, it is explained that while it is convenient to place "New car" and "Wreck" in one column on the manual, as shown, in view of the use of the two-way switch, it is better to have the "New car" category and the "Wreck" category on the signal board S in separate columns for obvious reasons.

If the car is promised at a definite time, the superintendent manipulates switch 10, which is an individual switch for time indication, to operate the time mechanism hereinafter described and give a proper reading on the dial 10c of transverse column 5S, car No. 1, under the "Time" vertical column head. Finally, he closes the appropriate switches 11 under "Mechanical" 75 and "Metal-paint," for instance, to energize the

corresponding signals $11a$, under the same headings on the board.

We, therefore, have the board reading in illuminated signals from left to right "Deliver," "Wreck," "Mechanical" and "Metal-paint," which signals remain in operation indefinitely along with the illumination of the dial $10a$ that shows the promised time of delivery.

The mechanics or workmen concerned in these operations now view the board. Suppose the first one that is free is the mechanical man. He is interested in signal $11a$ under "Mechanical" (car No. 1), finds and takes the car to his department or booth and starts working on it. He indicates the fact that he is working on it in the following manner:

In the same area of the vertical "Mechanical" column of the board is a small red signal light in the nature of a pilot light indicated at $7a$. This is controlled by the circuit closer of the jack socket 7 on manual M under the heading "Mechanical." At the right side of manual desk 2 (Figs. 6 and 7) is an angle bracket 14 having apertures therein for a plurality of jack plugs 15 and 16 , shown in detail in Figs. 8 and 9. These are numbered as shown and each workman has a number corresponding to the jacks or vice versa just as the incoming cars have the numbers $5S$. We will assume that this is workman No. 1. He takes his jack 15 of the corresponding number and inserts it in jack socket 7 of the manual under vertical column "Mechanical." This energizes pilot signal $7a$ just referred to and the superintendent thereafter inspecting the board knows, by the lighting of pilot light $7a$, that the mechanical job on car No. 1 is in progress. By looking at the manual and inspecting the number of the jack in socket 7 under "Mechanical," he knows that workman No. 1, in contradistinction to several other workmen that might have accepted the job, is engaged on it.

We now turn to the painter who observes signal $11a$ under the board heading "Metal-paint," which affects his department. He is temporarily at leisure and he also observes that car No. 1 is in the mechanical department and in work. By further inspecting the manual he can tell, in the same way that the superintendent did, that workman No. 1 is engaged on it. Without bothering the superintendent, he can, therefore, go to workman No. 1 and find out about when the car will be released for the next operation that he himself is to perform in the paint department.

When workman No. 1 in the mechanical department has finished with the car he goes to the manual, removes his jack No. 1 from jack socket 7 under the heading "Mechanical," the pilot signal light $7a$ is extinguished and then the superintendent knows that that part of the order has been fulfilled because the workman at the same time throws switch 11 and eliminates all signals under the vertical heading "Mechanical" or, of course, this can be done by the superintendent, according to the particular arrangement.

Workman No. 8, we will say (the painter), now gets car No. 1 from workman No. 1, moves it into the paint shop (signal $11a$ being still energized), inserts his jack 15 (numbered 8) in jack socket 7 under the "Paint" job vertical column and small pilot light $7a$ thereof becomes energized showing that the car has been thus transferred and is receiving attention.

So it goes along the whole line. But with respect to these jacks, each workman has a jack

15 (Fig. 8) and a jack 16 (Fig. 9) both bearing his number. They are distinguished in some arbitrary manner, as by the fact that that shown in Fig. 16 has a red band around the head thereof while the other is plain. This provision is made for the following purpose: Suppose workman 1 is engaged on a long job in the mechanical department on car No. 1. Car No. 2 comes in, requiring a relatively short period of mechanical attention. Workman No. 1 is the only mechanical man available. It is desired to dispose of car No. 2 because car No. 1 is a long job and there is plenty of time anyway. Workman No. 1, therefore, accepts the job on car No. 2, places red jack 16 in the jack socket 7 of car No. 2, horizontal row, at the same time leaving his plain jack No. $v5$ in the same socket 7 of car No. 1. The result is that the superintendent returning to his station, consulting the board and observing the two jacks on the manual at once sees that workman No. 1 is working on both cars at the same time and that both are, therefore, receiving attention by the same man. When workman No. 1 completes his temporary diversion to car No. 2, he returns to the manual, withdraws his red plug No. 1 and restores it to the rack 14 and goes back to his work on car No. 1.

Of course, when the said car No. 1 is serviced in all departments, the slip and holder 1 is removed, the signal switches affecting the same in that horizontal row are all restored to neutral and all of the plugs 15 and 16 are restored to rack 14 ready for the advent of another car to be treated under the same numerical designation.

With respect to all of the pilot or working lights appearing on the board in connection with the various operation designations, the action is the same but with respect to the first vertical column under "Deliver," it is explained that the pilot light there indicates that the car is on its way to the customer. In other words, the drivers who perform this particular function have numbered jacks on the rack 14 just like the workmen and when they take a car out for delivery, they place their individual jack in the delivery socket removing it when they return to the shop and extinguishing the pilot light.

One skilled in the art to which the invention appertains could, with the apparatus above described, devise circuits effecting the results to be accomplished between the jacks and switches of the manuals and the signals of the signal boards. However, to complete the disclosure, I have shown in Fig. 6 a diagram of one such circuit plan. The switch at the left hand end of the diagram concerns "Delivery" signal $6a$ on the board S and "Wait" signal $9a$ in the first and second vertical columns thereof respectively. These are alternative instructions, as explained. Hence, switch 9 is a two-way switch and the single vertical column on the manual for it and the jack 6 controls the first two vertical columns of signals $6a$ and $9a$ of the signal board S , together with (indirectly) the pilot or attention signal $7a$ of the first column. When the superintendent wishes to register a "Wait" job, switch 9 is thrown to the right in the diagram and closes a circuit from battery 4 through wire 17 , wire 18 , the said switch contact 19 , wire 20 , signal $9a$, wire 21 and negative wire 22 back to battery 4 , wires 17 and 22 being respectively positive and negative wires of the energizing circuit between which all of the signaling circuits are arranged in parallel. This simple circuit through that signal is all that is

required because the said "Wait" designation is a matter of information and not instruction.

On the contrary, the "Delivery" designation of the first vertical column is a matter of instruction—hence the provision of the pilot or attention light 7a and the jack sockets 6 associated therewith. In the event that delivery is required, switch 9 in the diagram is thrown to the left instead of to the right to a contact 23. This contact leads through a wire 24 to a two-way switch 25 normally closed on a contact 26 leading through a wire 27 to signal lamp 6a and thence through wires 21 and 22 back to battery 4. Switch 25 of the diagram does not appear on the manual as such because it is operated only by a jack plug in socket 6.

This is the initial energizing of the "Delivery" signal 6a. When the workman charged with this "Deliver" activity observes this signal 6a and is at liberty to assume the job, he takes his jack 15 and inserts it in jack socket 6. The effect of this is to throw switch 25 from normal contact 26 to contact 27 on a parallel circuit including wire 28, pilot signal 7a, wire 29 and wire 22 back to the negative side of battery 4. The "Deliver" signal 6a will be extinguished by the jack but the pilot 7a energized showing that the driver workman is on the job and that the car in question is on its way to the customer. Upon the return of this workman or driver, he removes his jack aforesaid, also throws switch 9 to neutral and both signals 6a and 7a are restored, closing the transaction with respect to car No. 1 or whichever it may be. On the same principle, the next switch 9c at this left end of the manual row connected by a wire 30 from positive lead 17 may be thrown to the right to a contact 31 which through wire 32 energizes "Wreck" signal 9c and thence the circuit continues to negative parallel 22 through wire 33 or the switch may be thrown to the left to contact 34 and through wire 35 energize signal 9b indicating "New car."

Returning to the matter of the "Time" designation 10a before referred to and having in mind the purpose thereof previously described, the object is to place under the control of the said superintendent who supervises the manuals M and M' and hence the recordings of the boards S and S' connected therewith the capacity to manually control such stop clock system 10a with which the board S is furnished. In the present embodiment, such dials 10a are repeated in the vertical column under "Time" so that one such dial appears in each horizontal row under the car entries in the shop, 1 to 15. These dials are translucent and the time indication is made by a rotary illuminated hand 36 (Figs. 15, 16 and 17) that rotates in rear thereof. The hand is also translucent but carries the electrical light bulb 37 in rear thereof so that in any of its positions its brilliance is cast upon the said translucent dials in distinguishing arrangements with the surrounding numbers 38 thereof. Switch 10 controls both the mechanical rotary operation of hand 36 and the accompanying illumination thereof through bulb 37. The said hand 36 is mounted on a shaft or spindle 39 suitably mounted in a bearing bracket 40 to which spindle is fixed a ratchet 41, all of this mechanism being enclosed within or attached to a suitable casing 42 mounted on the back of board S, there being such mechanism for each of the 15 cars provided for. Associated therewith is a suitable low voltage motor in the casing 42 embodying a crank

arm 43 on the shaft thereof. A wrist pin 44 on this crank is connected to a link 45 restrained by a spring 46. The said link 45 has a pallet tooth 47 cooperating with the teeth of the ratchet 41 whereas a spring detent 48 prevents retrograde movement of the ratchet wheel. The idea is that as long as the circuit to the motor is held closed the crank 43 will continue to revolve and as it passes and repasses its center the link 45 will, through the tooth 47, communicate the current impulses to the ratchet 41 and keep the indicator hand 36 revolving in a clockwise direction. It is obvious that this movement of the hand will continue as long as the circuit is closed but at any point at which it is opened or interrupted the hand will stop at the desired designation on the dial 38.

The operating control and electrical connections of this time registering mechanism appears at the central portion of the diagram of Fig. 6. Switch 10 is a two-way switch which when thrown to the right is adapted to cooperate simultaneously with two contacts 91 and 92 and when thrown to the left to engage with a single contact 98. The first mentioned movement is made when the superintendent wishes to set the clock to a particular reading. In that case, the circuit is closed from battery 4, wire 17, wire 90, switch 10, wire 96, the signal light on the hand of the dial 11a, wire 97, and back through wire 22 to battery. This illuminates the hand and dial. At the same time, a circuit is closed from battery, wire 17, wire 90, switch 10, contact 92, wire 93, motor 42, wire 94 and back to battery through wire 22, thus energizing the motor so that the hand revolves. When the hand reaches the desired reading, the switch is thrown out breaking both of these circuits but it is immediately transferred over to contact 98 which closes the parallel circuit, battery 4, wire 17, wire 90, switch 10, contact 98, wire 95, a portion of wire 96 to the hand signal lamp, wire 97 and back to battery through wire 22 so the motor remains de-energized but the dial and hand remain illuminated for the observation of the workmen and the purposes first above generally set forth. This switch, of course, has a normal neutral position as the dial light is energized only when the car of this number is in the shop and even then it is not always necessary to set a time limit.

We now come to the right side of the signal board S and manual M bearing the column designated "Wash," "Lubricate," "Mechanical," "Metal-paint" (which latter is not a double column but a joint service department) and ending with the "Operator" column of designations. In the diagram only one of these four groups of service signals is designated and hence only one of the switches 11, so that they may be taken to represent any one of these allocations. However, switches 11 are snap switches without neutral positions and the one shown is normally on contact 49 in a normally open circuit as will appear. When it is reversed by the superintendent to designate the service required, say, "Wash," it is thrown oppositely to a contact 50 closing a circuit from battery 4, wire 17, wire 51, switch 11, wire 52, signal 11a, wires 53 and 22 and back to battery. As before, when the workman takes charge of the car in response to such signal, he inserts his jack plug 15 in the corresponding socket 7 that actuates and thereby closes normally open contact member 54 against contact 55. At the same time he reverses switch 11 back

to contact 49, extinguishing call signal 11a. This closes the circuit through the "Wash" or corresponding pilot light 7a on the board as follows: battery 4, wire 17, wire 51, switch 11, wire 56, contact 54, contact 55, wire 57, pilot 7a, wire 58 back to battery through wire 22. On completion of the job, the removal of the jack plug extinguishes the pilot light which establishes that fact and all circuits are restored to normal.

Attention is now directed to the last column of signals 59 on the board S under the heading "Operator" and the reader is here warned that these bear no direct relationship to the last column of plug sockets 8 on the manual M. The function of the former is merely to indicate at a glance that a particular car 1, 7 or 15 is being worked upon somewhere in the establishment. I, therefore, provide means for automatically energizing this signal with the lighting of any one of the pilot lights 7a with the exception of the pilot light on the designation "Deliver" because, obviously, when the driver is with that car it is out and not in the shop. This means is shown beyond the break at the right of the diagram. When contact 54 is closed against contact 55, as previously described, it also makes connection with the contact 60 and the following circuit is established through signal 59: battery 4, wire 17, wire 51, switch 11, contact 49, wire 56, contact 60, contact 54, wire 61, signal 59, wire 62, and through wire 22 back to battery. It is broken, of course, with the removal of the jack plug that energizes any particular pilot light but signal 59 is in parallel with all of the pilot light circuits so as long as any one of the latter is energized this same signal 59 will remain energized.

The horizontal row of signals 63 at the top of signal board S bearing numerals running, in the present instance, from 1 to 11 has no connection with either the card identification designations 5S or the workmen's numbers on the jack plugs 15 and 16. On the contrary, it identifies what may be termed the various "stalls" in the establishment, some of which may accommodate several cars at one time or may not as the paint shop in the one case and the individual wash racks in the other. The superintendent may wish to know which of these departments are busy. All of the signals 63 which, as in the other cases, consist of translucent windows with lamps behind them, are normally energized, that is, a particular stall is empty when its light is on. The circuit so established as shown in the diagram of Fig. 6 is battery 4, wire 17, wire 64, through a contact 65 normally closed on a contact 66, wire 67, signal 63, wire 68 and back to battery through negative wire 22.

Turning now to the last column of jack plug sockets 8 on the manual M, workmen when not engaged leave their primary jack plugs 15 in these sockets 8, the rack 14 being utilized for extra jacks and the secondary colored jacks 16. The sockets 8 are conveniently numbered with the same column of numbers 69 at the right hand end of the manual that can be incidentally utilized at this point for identifying the cars received. If, for instance, a workman responding to a call signal is a washer and stall 11 of the signal 63 is his wash rack, he removes the plug from the 11th socket 8 when he takes charge of the car. This extinguishes this particular signal 63 of stall 11 because the presence of the jack is what holds contacts 64 and 66 normally closed. When

he finishes the job he returns the jack to the same place allowing contacts 64 and 66 to close and re-energize the signal 63 to indicate the empty space in that department.

If it will be borne in mind that the horizontal top row of numbered stall signals 63 on board S have no numerical relationship or connotation with the other columns and rows of signals and designations on this board, the arrangement 10 thereof that it has been found convenient to adopt will not cause confusion. The same is true of the column of plug sockets 8 at the right of the manual, so far as board S is concerned, though utilized on the manual itself for the purposes described. In the same way the plug sockets 8 have nothing to do with the signals 59 though similarly arranged on the two instrumentalities.

I will now describe the mechanical arrangements of the manual M whereby the shop record, card or slip of a particular car giving the name, license, etc. for the written record, as first explained, is inserted thereon. Each card or slip lies between a pair of clamping ribs 70 having stems 71 extending down through slots 72 in the table or desk 73 that constitutes the surface of the manual. These stems are spaced by tubular members 74 and held together for joint actuation by cotter pins 75 extending through the stems and tubes. A bowed leaf spring 76 reacting at its center against the underside of the table has its ends engaged with the member 75 under tension. The ribs 70 therefore normally operate as clamps that draw down against the table and hold the slip or card securely in the space 1 for writing purposes. To release them, there is supported in brackets 77 depending from the underside of the table a yoke 78 having pivotal bearings 79 and 80 therein. Connecting the arms of the yoke is a rod or roller 81 off of the center 79-80. The axis thereof and the yoke itself runs transversely of the column of spaces 1 and holders 70 and the stems 71 thereof are continuous flanges, as appears in Figs. 13 and 14. Pivot 80 is extended to the front of the manual, as shown also in Fig. 7, to terminate in an accessible hand knob 82. When this knob is turned to the left, as in Figs. 11 and 13, the rod 81 of the yoke is rotated downwardly to clear the stem flanges 71 and the springs 76 hold the clamping ribs 70 in operative or clamping position. When the knob is rotated to the right, as in Figs. 12 and 14, the rod 81 engages the stem flanges 71, rides upon them and tilts them upwardly as it moves to a dead center and thereupon the slips or cards may be slid in or out beneath the clamping flanges.

With an apparatus constructed and functioning substantially in accordance with this disclosure, much time and confusion can be saved particularly in the larger automobile sale and service stations. The superintendent has before him at all times full identification of all the cars that have entered the shop, where they are, what has been done to them, the jobs that remain and the time delivery is promised either to the waiting customer or at an outside point. He also knows at a glance at signal board and manual the person working on the car at the time. The workmen on the other hand, by consulting the board without bothering the superintendent, can immediately see the work that lies ahead of them, whether a particular car is accessible or not for their immediate attention and from where they may expect to obtain or receive it. In the meantime, persons from the office can

answer inquiries without consulting any body by mere inspection of the board.

In this last connection, it is pointed out that the manual M and signal board S or S' may be located at relatively remote points, and it is obvious that the signal boards may be duplicated at widely separated points as in the shop and also in the office with both operated from the shop manual simultaneously.

Although, as far as I am now informed, my invention in all its aspects is of greatest utility in an automobile service establishment, important features thereof might well be employed in other activities which have in common similar usages and requirements.

I claim as my invention:

1. In a signaling system embodying a display register of ordered acts, the combination with a signal board having a column of designations of units to be entered for attention, a plurality of relatively transverse rows of designations of different acts to be selectively performed upon said units, a signal for each such act designation in each row individual to that particular unit thereof, a selective control board embodying banks of circuit closers, individual pilot signals associated with appropriate individual designations to indicate response thereto, and electrical circuits connecting the respective circuit closers with the respective signals including the pilot lights.

2. In a signaling system embodying a display register of ordered acts, the combination with a signal board having a column of designations of units to be entered for attention, a plurality of relatively transverse rows of designations of different acts to be selectively performed upon said units, a signal for each such act designation in each such row individual to each particular unit of the unit column, a selective control board embodying banks of circuit closers, pilot signals on the signal board associated with appropriate individual act designations of the said rows to indicate response thereto, the circuit closers for the pilot signals embodying jack sockets, a plurality of jacks respectively having prearranged characteristics identifying them with different individual workmen, and electrical circuits connecting the respective circuit closers with the respective signals.

3. In a signaling system embodying a display register of ordered acts, the combination with a signal board having a column of designations of units to be entered for attention, a plurality of relatively transverse rows of designations of different acts to be selectively performed upon said units, a signal for each such act designation in each such row individual to each particular unit of the unit column, a signal common to all the act designations of the same kind in all the rows, a selective control board embodying banks of circuit closers, pilot signals on the signal board

associated with appropriate individual act designations of the said rows to indicate response thereto, the circuit closers for the pilot signals embodying jack sockets, a plurality of jacks respectively having prearranged characteristics identifying them with different individual workmen, and electrical circuits connecting the respective circuit closers with the respective signals, the jack of the pilot signal of a particular act designation being also adapted to affect the signal circuit for the said column acts in all the rows.

4. In a signaling system embodying a display register of ordered acts, the combination with a signal board having the designation of a unit to be entered for attention, a plurality of designations on the board of different acts to be selectively performed upon said unit, a signal for each such act designation, a pilot signal associated with appropriate act designation signals to indicate the performance of each such act, a selective control board embodying banks of circuit closers, and electrical circuits connecting the respective circuit closers with the respective signals.

5. In a signaling system embodying a display register of ordered acts, the combination with a signal board having the designation of a unit to be entered for attention, a plurality of designations on the board of different acts to be selectively performed upon said unit, a signal for each such act designation, a pilot signal associated with appropriate act designation signals to indicate the performance of each such act, a selective control board embodying banks of circuit closers, electrical circuits connecting the respective circuit closers with the respective signals, and an additional signal in circuit with all of the pilot signals designating the same act to be energized as long as any one of them is closed.

6. In a signaling system embodying a display register of ordered acts, the combination with a signal board having a column of designations of units to be entered for attention, a plurality of relatively transverse rows of designations of different acts to be selectively performed upon said units, a signal for each such act designation in each row individual to that particular unit thereof, a selective control board embodying banks of circuit closers arranged in duplication of the arrangement of the said signals, electrical circuits connecting the respective circuit closers with the respective signals, a clock dial in each act designating row, an indicator signal therefor embodying a hand and a lamp for selectively illuminating the same, and a motor device for rotating the latter, the corresponding circuit closer on the control board and its circuit to the hand signal being also adapted to energize the motor.

WILLIAM H. CLEHM.
